UNITED STATES PATENT OFFICE.

ALFRED W. GLASS, OF DETROIT, MICHIGAN.

DESIGN FOR A BURIAL-CASE.

SPECIFICATION forming part of Design No. 19,286, dated August 27, 1889.

Application filed July 24, 1889. Serial No. 318,557. Term of patent 3½ years.

To all whom it may concern:

Be it known that I, ALFRED W. GLASS, a citizen of the United States, residing at Detroit, county of Wayne, State of Michigan, 5 have invented and produced a certain new and original Design for a Burial-Case; and I declare the following to be a full, clear, and exact description of the same, such as will enable others skilled in the art to which it applies to make and use the same, reference being had to the accompanying drawings, which form a part of this specification.

In the drawings, Figure 1 is a view in perspective of the shell of a burial-casket with 15 the cover removed. Fig. 2 is a plan view thereof.

The leading feature of my design consists in the new and original form or shape of the ends of the shell and that produced by their 20 union with the sides of the shell.

In explanation thereof, A A represent the sides of the shell, and B B the ends. These ends are formed on an arc or segment of a

circle less than a half-circle, and forming at the point of the union of the ends and sides 25 of the shell defined corners a a', as illustrated in the drawings. The sides of the shell are carried straight out to said corners, and a line drawn from corner to corner would form the chord of the segment of the circle on 30 which said ends are constructed.

The design as a whole consists of a burial-case of oblong shape having ends of curved form, the extremities of the curved ends forming angles with and not merging into 35 the planes of the sides.

What I claim as my invention is—

The design for a burial-case, as herein shown and described.

In testimony whereof I sign this specification in the presence of two witnesses.

ALFRED W. GLASS.
